PENCIL SHARPENER

Howard W. Jenkins, Henderson, Ky.

Application January 26, 1937, Serial No. 122,465

1 Claim. (Cl. 120—96)

This invention relates to pencil sharpeners and has for an object to provide a pencil sharpener including a grinding wheel having a concave periphery and a holder adapted to position the pencil tangentially and centrally on the concave periphery of the grinding wheel so that the resultant sharpened point will be a surface generated by a moving arcuate line passing through a fixed vertex instead of the ordinary conical surface to the end that more wood will exist at the lead than exists where the usual sharpened conical point is made and thus the lead will be reinforced at its juncture with the wood to a greater extent than hitherto possible.

15 A further object is to provide a pencil sharpener of this type in which the parts will be concealed in a transparent casing so that the grinding operation may be clearly seen, there being a guard carried by the casing to prevent the sawdust following the wheel in the direction of rotation.

20 A further object is to provide a pencil sharpener of this type having a vertically adjustable pencil holder to position the pencil relatively to the grinding wheel so that the sharpened point may be a long keen point or a stub point and also to allow adjustment of the holder to compensate for any possible wear on the wheel.

25 With the above and other objects in view the invention consists of certain novel details of construction and combinations of parts herein-after fully described and claimed, it being understood that various modifications may be resorted to within the scope of the appended claim without departing from the spirit or sacrificing any of the advantages of the invention.

In the accompanying drawing forming part of this specification,

30 Figure 1 is a plan view of a pencil sharpener constructed in accordance with the invention.

Figure 2 is a front elevation of the pencil sharpener shown in Figure 1.

35 Figure 3 is an end elevation of the pencil sharpener with parts broken away.

40 Referring now to the drawing in which like characters of reference designate similar parts in the various views, 10 designates a base upon which preferably an electric motor 11 is secured by screws 12. The shaft of the motor is equipped with a grinding wheel 13 the same being clamped on the shaft between a collar 14 and a washer 15, the latter being held in place by a nut 16 which is threaded on the end of the shaft.

45 The periphery 17 of the grinding wheel is con-

cave or dished from edge to edge as best shown in Figure 1.

A transparent casing 18 is removably supported on the base by means of spring clips 19 which engage in openings 20 in the casing as best shown in Figure 3. The casing houses the motor and the grinding wheel and collects the sawdust while at the same time permitting the sharpening operation to be viewed by the operator.

5 A downwardly directed shield 21 is secured at the upper end to the front of the casing by a bolt 22. The shield slopes downwardly toward the bottom of the grinding wheel and prevents sawdust from following the wheel around in the direction of rotation and consequently the clear 15 vision of the sharpening operation is not obstructed at any time.

The pencil holder comprises a pair of aligned tubes 23 and 24 which are carried by respective plates 25 and 26 that are adjustably clamped 20 against the inner face and the outer face of the front wall of the casing by bolts 27 and 28 which pass through vertical slots 29 and 30 formed in the front wall of the casing.

25 A guide tube 31, having a flared outer end 32, 25 is axially received in the aligned tubes 23 and 24. The guide tube 31 positions the pencil 33 to extend tangentially with respect to the periphery of the grinding wheel and also centers the pencil on the periphery midway between the side edges 30 of the grinding wheel. A leaf spring 34 is secured to the top of the casing by a bolt 35 and extends downwardly into the space between the inner end of the guide tube 31 and the grinding wheel 13. This spring exerts pressure upon the 35 pencil during the sharpening operation.

An electric lamp 36 is mounted on a housing 37 which is placed over the motor 11 and is secured to the base by screws 38. The lamp and the motor are energized from the same supply 40 wires 39 so that when the motor is running the lamp will be lit. A switch 40 is disposed on the base and controls the supply of current to the motor and to the lamp.

45 While a motor has been illustrated as furnishing the driving power for the grinding wheel the motor may be dispensed with in some instances and the grinding wheel shaft may be hand operated by any well known type of step-up gear mechanism.

50 By virtue of the concave grinding surface, and by virtue of the guide tubes positioning the pencil tangentially to this surface and centered thereon, the pencil will be sharpened to present a wood surface which may be said to be a surface 55

- traced by a moving arcuate line passing through a fixed vertex. Consequently there will be more wood at the juncture of the lead than ordinarily is found where the pencil is sharpened to a conical point and in practice it is found that the sharpened end of the pencil is shorter by virtue of this novel surface contour than ordinarily is the case where the pencil is sharpened to a conical point.
- 10 By adjusting the guide tube 31 vertically in the vertical slot 29' the user may vary the position of the pencil with respect to the grinding wheel at will and thus accomplish the dual function of regulating the sharpened point to a stub point, and also permitting adjustment of the tube to compensate for any wear on the wheel.
- 15 From the above description it is thought that the construction and operation of the invention

will be fully understood without further explanation.

What is claimed is:

A pencil sharpener comprising a base, a revolvable grinding wheel mounted thereon and having a concave periphery, a transparent casing fashioned with a pencil receiving slot and secured to the base and housing said wheel, a pair of aligned tubes clamped to said casing about said slot and vertically adjustable on said casing, and a guide tube extending through said first mentioned tubes and adjustable therewith to position a pencil tangentially to the wheel and within said concave periphery, said casing coacting with said tubes to permit the end of a pencil to be viewed and adjusted into operating engagement with said wheel from the exterior of said casing.

HOWARD W. JENKINS.
